UNITED STATES PATENT OFFICE

ALDEN P. CHESTER, OF KOKOMO, INDIANA, ASSIGNOR TO GLOBE AMERICAN CORPORATION, OF KOKOMO, INDIANA, A CORPORATION

DESIGN FOR A COOKING RANGE

Application filed March 27, 1933. Serial No. 47,604. Term of patent 7 years.

To all whom it may concern:

Be it known that I, ALDEN P. CHESTER, a citizen of the United States, residing at Kokomo, in the county of Howard and State of Indiana, have invented a new, original, and ornamental Design for a Cooking Range, of which the following is a specification, reference being had to the accompanying drawing, forming part thereof.

Fig. 1 is a front perspective view of a cooking range, showing my new design.

Fig. 2 is a side elevation thereof.

I claim:

The ornamental design for a cooking range, as shown.

ALDEN P. CHESTER.
